POLARIZED ELECTRICAL CONNECTOR

Wallace A. Stanley, Birmingham, Mich., assignor to
Watts Electric & Mfg. Co., Birmingham, Mich., a corporation of Michigan

Filed Jan. 18, 1960, Ser. No. 2,905

10 Claims. (Cl. 339—184)

The invention relates generally to connector structures and refers more particularly to improved connector structures including means to prevent the assembly of the connector units thereof in other than predetermined relative angular positions.

One of the purposes of the present invention is to provide connector structure including means to prevent assembly of the connector units thereof in other than a particular predetermined relative angular position.

Another object is to provide a connector structure including means for determining the relative angular relation of the connector units thereof in assembly.

Another object is to provide a connector structure including chevron type contact members whereby the relative angular position of the connector units of the structure in assembly may be predetermined.

More specifically it is an object to provide a bulb socket having chevron type contact members at one end thereof which bulb socket is adapted to receive an electrical bulb at the other end, and an electric connector including chevron type contact members adapted to interfit with the contact members of said bulb socket and to which electrical conductors are connected, which bulb socket and electric connector are adapted to be engaged in relative angular positions determined by the orientation of the chevron type contact members to connect the light bulb with the electrical conductors.

Another object is to provide connector structure as set forth above including a male chevron type contact member comprising an elongated member of conductive material including a V-shaped transverse cross-section at one end thereof and also including means adjacent the other end thereof for preventing withdrawal of the contact member from a member in which it is mounted.

Another object of the present invention is to provide a connector structure as set forth above including a female chevron type contact member comprising an elongated member of conductive material including at one end thereof a V-shaped cross-section having the outer ends of the V open-returned to provide space for insertion of a male chevron type contact member and also including means at the other end thereof for preventing withdrawal of the contact member from a member in which it is mounted.

Another object of the present invention is to provide connector structure including means permitting assembly of the connector units only in predetermined relative angular positions, which connector structure is simple in construction, economical to produce and efficient in use.

Other objects, advantages and novel details of construction of this invention will be made more apparent as this description proceeds, especially when considered in connection with the accompanying drawings, wherein:

FIGURE 1 is a partially broken away side view of a bulb socket connector unit including female chevron type contact members.

FIGURE 2 is a left end view of the bulb socket illustrated in FIGURE 1.

FIGURE 3 is a cross-section view of the bulb socket illustrated in FIGURE 1 taken on line 3—3 in FIGURE 1.

FIGURE 4 is a sectional view of an electric plug connector including male chevron type contact members.

2

FIGURE 5 is a right end view of the electric plug connector of FIGURE 4.

FIGURE 6 is a perspective view of a female chevron type contact member.

5 FIGURE 7 is a perspective view of a male chevron type contact member.

FIGURES 8a, 8b and 8c illustrate possible positioning of chevron type contact members to provide different predetermined relative angular positions for connector units.

With reference to the figures, a particular embodiment of the present invention will now be disclosed.

One embodiment of the invention is illustrated in FIGURES 1—7. In FIGURE 1 there is shown an electrical bulb socket, generally indicated 12, including a core 14 having secured therein female chevron type contact members 16. The connector structure further includes the electric connector, generally indicated 18, having male chevron type contact members 20 secured therein.

15 20 The male contact members of the electric connector 18 are adapted to be connected at one end to electrical conductors 22. The bulb socket 12 of the connector structure is adapted to receive a light bulb (not shown) in one end thereof.

25 30 The electrical connector is adapted to be connected to the bulb socket by means of the mating chevron type connectors 16 and 20 when the bulb socket and electric connector are in a predetermined relative angular position. Assembly of the electric connector and electric bulb socket of the connector structure in other predetermined relative angular positions is prohibited due to the use of the chevron type contact members.

More specifically bulb socket 12 comprises socket tube 24 having a flange 26 and finger means 28 at one 35 end thereof to facilitate connection thereof to appropriate structures (not shown). Socket tube 24 further includes an annular radially inwardly extending flange 32 at the other end thereof against which one end of a spring 34 is abutted. Bayonet grooves 38 are also provided in socket tube 24 to engage lugs on a light bulb (not shown) received in the end 30 of the socket tube 24.

40 45 Insulating core 14 is inserted in end 36 of socket tube 24, as shown, and is biased into position abutting annular groove 42 centrally located on the socket tube by means of the spring 34 acting between the flange 32 and a flange 44 on core 14. Core 14 is provided with a transverse recess 46 across end 48 thereof, as shown best in FIGURE 3 to receive one end of a contact member 16 secured in openings 50 in core 14 as shown.

Core 14 is further provided with an axially extending groove 51 in the outer surface thereof as shown. Groove 51 cooperates with radially inwardly extending projection 53 on socket tube 24 to provide a splined connection therebetween whereby relative axial movement between the core and socket tube is permitted while relative rotation 55 therebetween is prevented.

50 60 Female chevron type contact members 16, as shown best in FIGURE 6, are provided extending through openings 50 in core 14 as shown. According to the invention the female chevron type contact members may be formed from an elongated strip of conductive material by means of forming one end 52 so that it presents a V-shaped transverse cross-section and then open-returning the edge portions 54 of the elongated strip to provide open pockets 56 into which the V-shaped cross-section of a male chevron type contact member may be received.

65 70 End 58 of the elongated strip of the female chevron type contact member may be narrower than end 52 thereof and includes a portion 60 extending substantially perpendicularly to the axis of the contact member which portion is adapted to secure the contact member in position within the core 14. The perpendicularly extending por-

tion 60 of the contact member 16 is adapted to fit within the recess 46 in the core 14 to present a substantially level surface for contacting the terminals of a light bulb inserted in the socket tube 24.

Electric connector 18, as shown best in FIGURE 4, comprises an insulating body 62 having a recess 64 in end 66 thereof and passages 67 extending axially therethrough adapted to receive male chevron type contact members. The insulating body 62 is also provided with a bead 68 extending radially inwardly from the axially outer edge of the recess 64 which is adapted to fit tightly around the socket tube 24 with the electric connector 18 and the bulb socket 12 in assembly, whereby recess 64 provides an insulating boot for the bulb socket 12 which is substantially sealed by the bead 68.

The male chevron type contact members 20 shown in FIGURE 4 are provided with transversely extending portions 71 and 72 at end 73 thereof adapted to connect electrical conductors 22 thereto.

The male chevron type contact member 20 shown in FIGURE 7, comprises an elongated strip of conductive material having a transverse V-shaped cross-section. The contact member 20 of FIGURE 7 further includes a perpendicularly extending tab portion 75 on one end thereof adapted to fit within a recess such as 46 in core 14 to prevent withdrawal of the contact member from the core in one direction, while tabs 76 struck out from the contact member 20 prevent withdrawal of the contact member from the core in the other direction.

The portions 60 and 75 of the male and female contact members 20 and 16 respectively, as shown in FIGURES 6 and 7, are particularly useful where the contact members 20 are to be engaged by the terminals of a light bulb. Ends such as that on contact member 20 illustrated in FIGURE 4, are provided on the male and female contact members when these contact members are assembled in an electric connector as shown in FIGURE 4.

In use an electric bulb is inserted in bulb socket 12 with the terminals thereof in contact with the portions 60 of the female chevron type contact members 16. Electrical conductors 22 are connected to the male chevron type contacts 20 of the electric connector 18. The electric connector 18 is then inserted over the end 36 of the socket tube 24 and rotated relative thereto until the orientation of the chevron contact members is such that the male contact member may be inserted in the female contact member.

Thus an electrical connection may be completed between the electrical conductors 22 and the light bulb with the electric connector forming an insulating boot around the end 36 of the socket tube 24. Also, it will be noted that due to the chevron type contact members used in the connector structure illustrated that assembly of the bulb socket with the electric connector is possible only with the electric connector and bulb socket in a predetermined relative angular position. Proper polarity of electrical connections and angular orientation of members secured to the connector structure is thus accomplished without the use of additional structural members in a simple, efficient and economical manner.

As shown in FIGURES 8a, 8b and 8c the particular relative angular position of connector units of a connector structure in the above described assembly may be determined by the positioning of the chevron contact members. For example, with the four contact member structure illustrated in FIGURE 8a, it will be obvious that connection may be made between two connector units having such contact members with the connector units in relative angular positions spaced ninety degrees apart.

With chevron type contact members arranged in the manner shown in FIGURE 8b it will be obvious that a connector unit having two chevron type contact members positioned to be concave in the same direction as for example in FIGURE 5 may be assembled therewith only

in either of two relative positions spaced ninety degrees apart.

Similarly, four chevron type contact members of a connector unit may be arranged to provide assembly with similar connector units only in either of two relative angular positions one hundred eighty degrees apart as indicated in FIGURE 8c.

Also, with chevron type contact members positioned as indicated in FIGURES 1-5, assembly of the line connectors may be accomplished with the connectors in only one relative angular position.

While specific embodiments of the connector structure of the invention have been disclosed, it is obvious that many modifications of the connector structure will be readily apparent to those skilled in the art. Similarly modifications of applicant's novel chevron type contact members and particular arrangements thereof for use in a particular installation will readily suggest themselves as a result of the invention disclosed herein. It is the intention to include in the scope of the invention all such modifications.

What I claim as my invention is:

1. Electrical connector structure, comprising an electric bulb socket including a socket tube and an insulating core in one end of said socket tube, said bulb socket also including a contact member extending axially of said socket tube through said core and spring bias means acting between said core and socket tube to bias said core and contact member toward the other end of said socket tube, a separate electric connector also including a contact member secured therein, said contact members including chevron type interfitting portions operable to prevent engagement of said bulb socket and electric connector with said bulb socket and electric connector in other than predetermined relative angular positions.

2. Structure as claimed in claim 1 wherein said insulating core includes a transverse recess extending across the end thereof closest said other end of the socket tube and the contact member extending through said core includes a portion extending at right angles thereto operable to aid in securing the contact member to the core and located within the transverse recess whereby shearing of terminals from light bulbs secured in the bulb socket with a rotating movement is prevented.

3. Electrical connector structure, comprising an electric bulb socket including a socket tube and an insulating core in one end of said socket tube, spline means acting between said socket tube and said core for preventing relative rotation therebetween, said bulb socket also including a contact member extending axially of said socket tube through said core and spring bias means acting between said core and socket tube to bias said core and contact member toward the other end of said socket tube, a separate electric connector also including a contact member secured therein, said contact members including chevron type interfitting portions operable to prevent engagement of said bulb socket and electric connector with said bulb socket and electric connector in other than predetermined relative angular positions.

4. Electrical connector structure, comprising an electric bulb socket including a socket tube and an insulating core in one end of said socket tube, said bulb socket also including a contact member extending axially of said socket tube through said core and spring bias means acting between said core and socket tube to bias said core and contact member toward the other end of said socket tube, a separate electric connector including a body of insulating material having an opening therethrough and a contact member secured within said opening, said contact members including interfitting portions having a V-shaped cross-section operable to prevent engagement of said bulb socket and electric connector with said bulb socket and electric connector in other than predetermined relative angular positions.

5. Electrical connector structure, comprising an electric bulb socket including a socket tube and an insulating core in one end of said socket tube, said bulb socket also including a contact member extending axially of said socket tube through said core and spring bias means acting between said core and socket tube to bias said core and contact member toward the other end of said socket tube, a separate electric connector including a body of insulating material having an opening therethrough and a contact member secured within said opening, said contact members including interfitting portions having a V-shaped cross-section operable to prevent engagement of said bulb socket and electric connector with said bulb socket and electric connector in other than predetermined relative angular positions, said body of said separate electric connector including a recess in one end thereof adapted to form an insulating boot around said one end of said socket tube with said bulb socket and electric connector in engagement.

6. Structure as set forth in claim 5 and further including a radially inwardly extending annular bead integral with the insulating boot at the axially outer extremity thereof operable to seal the connection between the bulb socket and electric connector in engagement.

7. An electric bulb socket comprising a cylindrical socket tube, a generally cylindrical core of insulating material in one end of said socket tube, means operably associated with said socket tube for limiting movement of the core toward the other end of said socket tube, resilient means acting between the socket tube and core for urging the core toward said other end of the socket tube, axially extending openings through said core, contact members mounted in said openings including chevron type end portions extending toward said one end of said socket tube and means for securing a light bulb in said other end of the socket tube in resilient engagement with the opposite end portions of said contact members.

8. Structure as claimed in claim 7 wherein said core includes a transverse recess extending across the end thereof closest said other end of the socket tube and said opposite end portions of said contact members include a portion extending at an angle thereto operable to aid in securing the contact members to the core and located within said recess whereby shearing of terminals

from light bulbs secured in the bulb socket with a rotating movement is prevented.

9. Electrical connector structure, comprising an electric bulb socket including a socket tube and an insulating core in one end of said socket tube, said bulb socket also including a contact member extending axially of said socket tube through said core, a separate electric connector also including a contact member secured therein, said contact members including chevron type interfitting portions operable to prevent engagement of said bulb socket and electric connector with said bulb socket and electric connector in other than predetermined relative angular positions.

10. An electric bulb socket comprising a cylindrical socket tube, a generally cylindrical core of insulating material in one end of said socket tube, means operably associated with said socket tube for limiting movement of the core toward the other end of said socket tube, axially extending openings through said core, contact members mounted in said openings including chevron type end portions extending toward said one end of said socket tube and means for securing a light bulb in said other end of the socket tube in resilient engagement with the opposite end portions of said contact members.
